UNITED STATES PATENT OFFICE.

WILBERT J. JACKMAN, OF LIMA, OHIO.

HYDROCARBON-BURNER.

SPECIFICATION forming part of Letters Patent No. 562,537, dated June 23, 1896.

Application filed April 21, 1894. Serial No. 508,502. (No model.)

To all whom it may concern:

Be it known that I, WILBERT J. JACKMAN, a citizen of the United States, residing at Lima, in the county of Allen and State of Ohio, have 5 invented certain new and useful Improvements in Hydrocarbon-Burners; and I do hereby declare the following to be a full, clear, and exact description of the invention, such as will enable others skilled in the art 10 to which it appertains to make and use the same.

This invention relates to an improved hydrocarbon-burner, and belongs to that class thereof known as "vaporizers" and "air-mixers," in which the oil is vaporized as it 15 passes to the burner, and is mixed with a certain amount of air prior to ignition.

The object of the invention is to provide a burner of such construction that all the oil 20 will be thoroughly vaporized before passing to the burner proper, and another object is to provide for the vapor issuing to the burner in the form of a jet, so as to carry into the burner an appropriate quantity of air.

25 With these ends in view the invention consists, broadly, of a vaporizing-coil, a condensing-pipe connected therewith, a back-pressure pipe for receiving the unvaporized oil, a cut-off valve through which the vapor passes, 30 an air-mixer arranged upon the valve-casing, and a burner proper located above the mixing-chamber and communicating there with said burner.

The invention consists also in certain details of construction and novelties of combination which will be fully described, and hereinafter particularly pointed out in the 35 claims.

In the drawings forming a part of this specification, Figure 1 is a side elevation, partly in section, of my improvements. Fig. 2 is a vertical sectional view of the burner proper, mixing-chamber, and cut-off valve; and Fig. 3 shows a sectional view of a burner adapted 45 for use in heating-stoves, the burner shown in Figs. 1 and 2 being adapted principally for use in cooking-stoves.

In carrying out my invention I employ an oil-supply pipe A, which is connected with a 50 suitable tank or reservoir, (not shown,) and the oil is passed therethrough by gravity or by air-pressure, as desired. This pipe A

leads to a regulating-valve B, and connected with the opposite side of this valve is the re-tort or vaporizing-coil C, comprising several 55 turns c and the depending end portion c', which end portion is connected with a condensing-pipe D by means of a reducing-coupling d. This condensing-pipe D is considerably smaller in diameter than the pipe C, the 60 purpose of which is to cause any small unvaporized oil globules or particles passing therethrough to unite and separate from the vapor as the latter passes onward to the burner. The lower end of this pipe D is connected 65 with a pipe E by means of an elbow e, and this pipe E is connected with the cut-off valve F by means of a T-coupling e'.

In the opposite end of the coupling e' is screwed a pipe or cylinder G, closed at its end 70 by a cap g. This pipe I term a "back-pressure pipe," and its purpose is to receive any large globules of oil that may have passed through the coil without being thoroughly vaporized and been carried by their momentum past the 75 vapor-duct leading to the burner. Any oil entering said pipe is thus retained therein and prevented from passing onto the burner, and while so retained it is gradually vaporized by the heat from the hot vapors of the jet-orifice 80 when the burner is in full operation and then passes up into the burner.

Projecting upward from the cut-off valve F is a union f, which is adapted to receive my improved burner. This burner comprises a 85 pipe H, which screws upon the union f, and is contracted at its upper end, providing a very small aperture h for the passage of the vapor, thus causing it to issue in the form of a jet. Connected with the pipe H (either integrally 90 or by attachment) is a flash or drip pan I, said pan surrounding the pipe, and being provided with a surrounding flange i, of any suitable depth. Extending upwardly from the end of pipe H are the arms k k, supporting a mixing-chamber or hood K, which is provided with a closed top. Passing through this top and extending some distance into the chamber or hood is the delivery tube or pipe L, upon the upper end of which fits the burner proper, M, 95 the lower end of said tube or pipe being expanded to receive the commingled air and gas or vapor.

The hood K and depending portion of the

- tube L constitute an annular air-chamber above the jet-orifice, which receives and confines such parts of the vapor as do not pass into the tube L, and admixes air therewith.
- 5 The hood K also protects the jet of vapor from disturbance by air currents, and directs said currents to facilitate their admixture with the vapor.
- It will be noted that the tube L, pipe II, and 10 cut-off valve F are all in alinement with one another, so that the vapor has a straight and unobstructed passage into the burner.

The burner proper, M, comprises the upper perforated plate m and the lower plate m' , 15 secured to each other and separated a sufficient distance to permit the expansion of the mixed air and vapor within the same. Passing through the burner upon opposite sides of the center are the air flues or passages m^2 , which 20 serve to provide air at the point of ignition, thus insuring satisfactory combustion and also spreading the flame. The lower plate has a central opening m^3 , and surrounding the same is a collar or flange m^4 , by means of 25 which the burner is fitted and held upon the delivery-tube L.

The regulating-valve B and cut-off valve F are substantially the same in construction, each consisting of a cylindrical casing N, 30 closed at each end by means of screw caps or heads n and n' . Within this casing N is arranged the valve proper, consisting of two parts U^2 and U^3 , respectively connected by a screw and socket, as shown, each section having a head and flange n^4 , which fits and works in a rabbet U^5 , formed at each end of the cylinder, and between the ends of sections and the caps of the cylinder are arranged the packing-wastes n^6 . The valve or plug proper 40 has a passage n^7 , which is adapted to register with opening n^8 in the opposite side of the casing, and it will be observed that the diameter of these openings and also of the passage n^7 is considerably smaller than that of 45 the communicating pipes, the purpose of which is to give the vapor considerable pressure as it issues to the burner.

The valve or plug is made in two parts for the purpose of inserting it in the casing, and 50 by constructing it with heads at each end and packing them in the manner shown a perfectly gas and oil tight valve is obtained.

The valve is operated by means of a stem n^9 , which is threaded intermediate of its ends 55 and works in a threaded yoke n^{10} . This stem can be made in one piece or in two parts and connected by means of a socket. The diam-

eter of the bore n^7 can be made any suitable size, according to the purpose for which it is intended. In operation the oil is fed from 60 the tank by gravity or air-pressure and passed through the regulating-valve B, which has been previously set at the desired point. The oil then passes through the coil C, down into pipe D, through pipe E, valve F, and pipe H. 65 Here it flows out upon the flash or drip pan I, where it is ignited. While the oil upon the pan is thus burning, the oil passing through the coil C becomes vaporized, and passes through the same course as the oil previously described. It issues, however, from the pipe H in the form of a jet and passes up into the air-mixing chamber K, and the commingled air and vapor then pass through the tube L into the burner, where it is consumed, the combustion 75 being assisted by the air mixed in the chamber K and also brought into contact with the flame by means of the air flues or passages m^2 . The condensing-pipe D and contracted 80 passages of the valve and pipe H all tend to feed the vapor to the mixer with considerable force, so that a current or suction is created, thus drawing and commingling the air in a better manner.

Having thus described my invention, what 85 I claim is—

1. In a hydrocarbon-burner, the combination with a burner, and a retort, of a condensing-tube through which the vapor passes to the burner, and a supplemental pipe or 90 tube communicating at one end with the condensing-tube, and closed at its opposite end, and adapted to receive globules of unvaporized oil which are carried past the vapor-discharge orifice, said condensing-tube being of 95 relatively smaller diameter than its inlet and discharge connections.

2. In a hydrocarbon-burner, the combination with a vaporizing-retort, of a burner proper comprising an upper perforated plate, 100 and a lower plate, constituting an expansion-chamber, a central inlet for combined vapor and air in said lower plate, an annular hood arranged below the burner proper, a delivery-pipe extending through the top of the 105 hood and communicating with the inlet of the burner proper and a pipe provided with a jet-orifice through which vapor is supplied to the delivery-pipe.

WILBERT J. JACKMAN.

In presence of—

ROBERT WILSON,
H. S. PROPHET.
